UNITED STATES PATENT OFFICE.

ELY C. HUTCHINSON, OF OAKLAND, CALIFORNIA, ASSIGNOR TO PELTON WATER WHEEL CO., OF SAN FRANCISCO, CALIFORNIA, A CORPORATION OF CALIFORNIA.

FLUID-LEVEL REGULATOR.

Application filed May 10, 1922. Serial No. 559,904.

To all whom it may concern:

Be it known that I, ELY C. HUTCHINSON, a citizen of the United States, residing at Oakland, in the county of Alameda and 5 State of California, have invented certain new and useful Improvements in Fluid-Level Regulators, of which the following is a specification.

The present invention relates to a fluid 10 level regulator for fluid receptacles or containers whereby the fluid level within the receptacles or containers is maintained between maximum and minimum points.

The object of this invention is to provide 15 a construction controllable by the fluid level and pressure within the receptacle whereby a continuous supply of fluid from the source or storage is directed into or away from the receptacle, maintaining the fluid within the 20 receptacle between maximum and minimum predetermined levels.

The invention consists primarily in a fluid supply line leading from the sump or fluid supply and within which is mounted a continuously operated pump for forcing the 25 fluid under pressure through either of two branches of the line, one connecting with a receptacle and the other returning to the sump, the feed of the fluid to the receptacle 30 being controlled by the operation of an unloader valve in the return branch, which closes against the pump pressure and is vented to operate by both the pressure and level of the fluid within the receptacle.

35 With the above mentioned and other objects in view, the invention consists in the novel construction and combination of parts hereinafter described, illustrated in the accompanying drawings and pointed out in 40 the claims hereto appended; it being understood that various changes in the form, proportion, size and minor details of construction within the scope of the claims may be resorted to without departing from the 45 spirit or sacrificing any of the advantages of the invention.

To more clearly comprehend the invention, reference is directed to the accompanying drawings, wherein—

50 Fig. 1 indicates a diagrammatic view of an assembly, illustrating the preferred embodiment of my invention.

Fig. 2 is a sectional view through the fluid level and pressure valve within the receptacle.

55 Fig. 3 is a vertical sectional view of the unloader valve.

Referring more particularly to the drawings, wherein like characters of reference designate corresponding parts—1 indicates 60 a suitable fluid storage reservoir provided with an opening 2 which is closed by a valve head or cover 3 detachably secured to a ring 3' permanently mounted in the opening 2.

Fluid is supplied to the receptacle 1 65 through a fluid supply pipe 4' by a pump 4 which draws the fluid from a sump 4². This supply pipe 4' branches as at 5' and 5², branch 5' returning to the sump 4² and the branch 5² connecting with the receptacle 1 70 through a check valve 5.

In the return branch 5' is mounted an unloader valve casing 6, the inlet end 7 of the channel 7' therein receiving by-passed fluid, and the outlet end 8 continuing the fluid 75 through the branch 5' to the sump 4².

Within the casing 6, closing against the pressure entering the inlet opening 7, is a reciprocating unloader valve 9, pointed at its end, as at 10, and adapted to move up and 80 down within a guide chamber 12. The upper end of the casing 6 is formed with a chamber 13 and is closed by a head 14.

Within the chamber operates the piston 15 carried by the upper end of the valve 9 85 and of a diameter corresponding to that of the chamber 13. A vent 13' connects the lower end of the chamber 13 with the outlet 8 and a pipe 16 connects the upper end of the chamber with the interior of the receptacle 1, through the channel 17, in the head 3 which channel connects at one end with a bore 18 opening at one end into the interior of the receptacle 1. The bore is bushed as at 19 and within the bore reciprocates a piston 20 on the end of the reduced end 21 of which is formed a valve 22 adapted to close the open end of the bore and to move across the end of the channel 17. A second bore 23 is formed in the head 3, the same opening into 100 the interior of the receptacle 1 and said bore is bushed, as at 24, and within said bushing operates a reciprocating valve 25 guided at its outer end, as at 26, and operated through

the bell crank connection 27, to the end of which is connected a float 28 adapted to raise and lower with the fluid level within the receptacle 1.

- 5 The valve 25 is formed between its ends with a reduced portion 29 of a sufficient length to afford a communication between the channel 30, connecting bores 18 and 23, and a channel 31 leading from bore 23 and 10 connecting with the rear end of channel 18. The reduced portion 29 is also of a length so that when the valve 25 is moved to close the channel 30, said reduced portion will afford a communication between the channel 31 15 and a fluid inlet channel 32, connecting the bore 23 with the interior of the receptacle 1.
- In line with the channel 30 is a vent channel 33 connecting with a pipe 34, which leads to the sump 4².
- 20 The device being assembled as in the drawings and assuming that the fluid level within the receptacle is at its minimum, due to the drawing off of fluid through an outlet, not shown, the various parts operate in the following manner in the supplying of fluid to the receptacle 1 from the sump 4² by the continuously operated pump 4.

The lowering of the fluid level within the receptacle causes a corresponding dropping 30 of the float 28 which through its bell crank 27 moves the valve 25 inwardly causing the reduced portion 29 thereof to provide a connection between ports 31 and 33, releasing the pressure in rear of the piston 20, and the 35 portion 22 of the valve 21 being open to the fluid pressure within the receptacle 1, said valve 21 is moved inwardly, affording a fluid pressure within the channel 17, which pressure builds up in chamber 13 of the unloader 40 valve and acts against the piston 15 thereof. The continuous operation of the pump 4, during this period of closing of the unloader valve, causes a continuous supplying of fluid through the pipe 4', branch 5² 45 and check valve 5 into the container or receptacle 1. The fluid level as it rises in the container 1 causes a corresponding upward movement of the float 28 and on attaining its upper level the action of the bell crank 27 50 will cause an outward movement of the valve 25, closing port 33 and opening the connection between ports 31 and 32, which permits of the receptacle fluid pressure entering the port 32 to pass to port 31 and act on the rear 55 of piston 20, forcing the valve 21 outwardly, closing the communication of the end of channel 17 with the interior of the receptacle or container, and opening it to discharge oil from cylinder 13 through the port 30 into 60 channel 33 and outwardly around the valve 25 through the annular passage surrounding same. This enables the pump pressure acting against the tapered end 10 of the unloader valve 9 to raise the valve and pass 65 through the casing 6, discharging into the

sump 4² through the outlet 8, thus a continuous circulation through the pump and unloader valve is maintained.

From the above description it should be noted that the level of the liquid may be 70 regulated within the receptacle to prevent liquid from reaching or contacting with the receptacle carried controlling valve for the unloader, for insuring the operation of the unloader valve by vaporous or gaseous receptacle pressure, the liquid level being adapted for operating and controlling the admission of vapor to said valve. The unloader valve is independent of the receptacle and adapted to be mounted in any position 75 relative thereto without regard to the liquid level of the receptacle. The controlling valves operate at any two predetermined 80 levels of liquid in the receptacle which should be obvious to one skilled in the art 85 from the description and showing thereof in the drawings.

I claim:—

1. In combination with a receptacle for receiving the supply of fluid, a source of fluid supply, a fluid conveying line leading therefrom, said line branching to connect through one branch with the receptacle and through another branch affording a return to said source of supply, a pump within said fluid conveying line, an unloader valve within the branch line returning to the source of supply and closing against the pump pressure, a check valve within said other branch line, a fluid pressure connection between the receptacle and one side of said unloader valve, a valve operated by the receptacle fluid pressure and controlling the admission of pressure into or the release of pressure from said connection, and a master valve operated by the level of the fluid in 100 said receptacle for controlling the operation of said first valve.

2. In combination with a receptacle for receiving a supply of fluid, a source of fluid supply, a fluid feed line leading therefrom and connecting with the receptacle, a pump therein for removing fluid from the source of supply and transmitting the same to the receptacle, a check valve interposed between the pump and the receptacle, a fluid return connection leading from said line between the pump and check valve and returning to 110 said source of fluid supply, an unloader valve for controlling the passage of fluid through said return connection, a valve controlled fluid connection between said receptacle and one side of said unloader valve, whereby the receptacle pressure maintains 115 said valve normally closed, a pressure release port and a master valve operated by a variation of fluid level within the receptacle for admitting receptacle fluid pressure to said first valve for the operation thereof, said valves adapted to be so positioned when said 120

receptacle is supplied with fluid to afford a connection between said connection between the unloader valve and receptacle and said pressure release port, whereby pressure is released from said unloader valve and the fluid pumped is returned to the source of supply.

3. A device of the class described, including a receptacle for containing fluid of liquid and gaseous nature under pressure, a liquid supply for the receptacle, a main feed pipe leading from the liquid supply, a pump for continuously circulating liquid in said pipe, a branch feed pipe connecting the main feed pipe with the receptacle having a check valve therein, a return pipe from said main feed pipe to the liquid supply, an unloader valve in said return pipe mounted independent of the receptacle or relative to the fluid level, a control unit mounted in the container above the level of liquid having means operable for admitting receptacle pressure to the unloader valve, and for connecting it to an exhaust, and a float mounted in the container below the unit having a connection with the means in said unit for operating it relative to the level of liquid in said container.

4. A device of the class described, including a receptacle for containing liquid, and gaseous and vaporous fluid under pressure, a liquid supply for the receptacle, a main feed pipe leading from the liquid supply, a pump for continuously circulating liquid in

said pipe, a branch feed pipe connecting the main feed pipe with the receptacle having a check valve therein, a return pipe from said main feed pipe to the liquid supply, an unloader valve in said return pipe, and a controlling unit mounted in the receptacle having a vaporous and gaseous pressure actuated valve controlling the admission of and exhaust of fluid pressure from said unloader valve, and float-operated means controlled through the liquid level in the receptacle for governing the operation of the unit carried valve by fluid pressure.

5. A control device for governing the admission of fluid to a receptacle containing fluid under pressure, comprising a body mounted in the receptacle having a passage communicating with means the operation of which effects the control and feed of fluid to the receptacle, said body being formed with a pair of valve chambers, a fluid pressure operated valve in one of said chambers for controlling the first mentioned passage to admit fluid thereto or connect the passage with an exhaust, and a valve operable in the other chamber for controlling the operation of the first mentioned valve by fluid pressure, the last mentioned valve being controlled and operated according to the liquid level in the receptacle.

In testimony whereof I have signed my name to this specification.

ELY C. HUTCHINSON.
